UNITED STATES PATENT OFFICE.

JOHN W. WALLACE, OF JERSEY CITY, NEW JERSEY.

GAME APPARATUS.

No. 856,118.

Specification of Letters Patent.

Patented June 4, 1907.

Application filed June 1, 1903. Serial No. 159,502.

To all whom it may concern:

Be it known that I, JOHN W. WALLACE, a citizen of the United States, residing at 200 Seventh street, Jersey City, in the county of Hudson and State of New Jersey, have invented certain new and useful Improvements in Game Apparatus, of which the following is a specification, reference being had therein to the accompanying drawings.

10 My invention relates to games of chance and particularly to game apparatus therefor and has for its objects simplicity of construction and effectiveness of operation.

According to my invention I employ mechanical means whereby a circuit of the game playing medium can be controlled by one game operating motion and returned to normal after each play by a second motion.

For the purposes of my invention I employ 20 spherical bodies constituting the playing media and an inclined board provided with recesses or holes to catch and hold such bodies, such recesses or holes being preferably designed to be marked with a number or symbol indicating a count or reward. I also employ a magazine containing a predetermined number of playing bodies so arranged that but one shall be released at a time and shall constitute a play or turn. I also employ a 25 releasing means whereby the game body shall be removed for lodgment with a recess or hole and suitable means are provided whereby it shall be returned to the game body magazine.

30 I will now describe the device illustrated in the accompanying drawings and will thereafter point out my invention in claims.

Figure 1 is a longitudinal central section of a device embodying my invention. Fig. 2 is 35 a plan view of the same partially broken away. Fig. 3 is a longitudinal central section of the game body magazine. Fig. 4 is a vertical section on the line 4—4 of Fig. 1 showing a detail of the game body return, 40 and Fig. 5 is a similar section showing the game body return in operative position also shown in dotted lines in Fig. 1.

Referring to the drawings the casing 1 of my device is in the form of a box with a 45 movable back 2. The upper cover of the box is provided with an inclined light 3 that permits of viewing the game board, and to this cover various of the game body magazine elements are attached. Within the box and 50 inclined from the horizontal is a game board

4 provided with recesses or holes 5 and bearing various elements of the game body magazine. This board is secured to the siding of the box by suitable cleats 6, 7, which act also as buffers, and at the lower end of the game 55 board 4 and secured to the upright front of the casing 1, is a piece of rubber or other elastic material 8 that acts as a buffer. The game body magazine comprises a series of pieces of suitable material 9, depending from 60 the upper cover of the box, and a series of pieces 10, projecting upward and secured relatively to the game board 4 and adapted to break joint with each other by a space exceeding the width of a game body 11. Supported upon suitable springs 12 is a conduit 13 perforated to receive the depending and upwardly projecting retarding pieces 9 and 65 10, and this conduit is provided with a knob or push button a projecting through the 70 upper cover at a convenient point thereon. Below the game board is another board 14, provided with recesses or holes 15 corresponding to the recesses or holes 5 and this board operates on cleats or slides 16 one of 75 80 which is shown in Fig. 1. The board is controlled by two springs such as 17, which are adapted to hold the board 14 in rearward position to close or form a false bottom to the recesses or holes 5. The board 14 is provided with an operating bar 18 connected to the board by suitable thrust rods 35. Below the false bottom 14 is another board or 85 partition 19 arranged at an angle thereto and provided with converging sides 20, covered 90 at their lower ends to form a return chute 21. This return chute is held in position by a partition 22 that is attached to the game board and projects upward therefrom to form a 95 dam behind the rear end of the lower portion of the magazine. The return of the game body is effected by means of a cup 23, trunnioned on what is termed a lazy tongs movement 24, the movement being operated by means of a bifurcated thrust yoke 25 having 100 horizontal projections 26 operating on upright guiding studs 27. The horizontal projections 26 operate on pins 30 in the lower terminal arms of the lazy tongs. The upper part or shank 29 of the thrust yoke 25 is 105 adapted to enter a recess 28 in the magazine conduit. The cup 23 which returns the game body is trunnioned in a V-shaped yoke 36 pivotally connected to the upper terminal arms of the lazy tongs and sliding upon guide 11.

wires or bars 37. The cup is preferably trunnioned so that it inclines by gravity in position to receive and retain a game body from the return chute 21, and it is provided 5 with a stop pin 38 which normally engages the yoke 36 to hold the cup in this position. The cup also has laterally projecting pins 31, which are adapted to engage pins 32 projecting from the partition 22 so as to tip the cup to discharge the game body into the magazine.

It will be observed that the game body magazine is so constructed that the co-operation of its depending and upwardly projecting stops permits but one game body in a magazine chamber.

The operation of one turn or play of my device is as follows:—The push button *a* operating the magazine conduit shown in 20 Fig. 1 is depressed as shown in Fig. 3 and allows the game body 11 in the first magazine chamber to escape and run down the game board until it enters and is retained by one of the recesses or holes 5. The bar 18 is pushed 25 and as soon as the holes 5 and the holes 15 in the false bottom coincide the game body will be precipitated onto the board 19 and run by gravity into chute 21 and into the cup 23. The board is then in position for a second 30 turn or play and with the depression of the button *a* the thrust yoke 25 is caused to slide on its guides 27 and actuate the projecting pins 30 of the lazy tongs movement so as to operate the lazy tongs and force the cup 35 23 upward until its pins 31 strike the stationary pins 32 thereby discharging the game body into the first chamber of the game body magazine, or this dumping operation can be effected by the alternative construction 40 wherein the cup strikes the cover of the casting and is thereby tipped so as to discharge its game body.

It is obvious that various modifications may be made within the spirit and scope of 45 my invention.

What I claim and desire to secure by Letters Patent is,

1. Game apparatus comprising game bodies, a game board inclined to impel such 50 game bodies by gravity from their initial position, such game board having a plurality of holes to arrest in one of a plurality of positions the movement of the game body, retaining means at the top of the inclined game board for holding the game body normally in its initial position, common releasing means for releasing the game body from any one of its arrested positions, return mechanism for replacing the game body in its initial position, means for releasing the game body 55 from its initial position maintained by the retaining means, and a common manually operative device for actuating the means for

releasing the game body from its initial position and the return mechanism.

65

2. Game apparatus comprising a plurality of game bodies movable by gravity, an inclined game board upon which the game bodies are moved by gravity, a magazine for retaining game bodies in initial position at 70 the top of the inclined game board, and common manually operable mechanism for releasing the game bodies from the magazine and for returning them to the magazine.

3. Game apparatus comprising movable 75 game bodies, a magazine therefor, means for discharging the game bodies from such magazine, a game board having arresting means for the game bodies, collecting means, means for carrying the game bodies from the lowermost position upward to the magazine, such means including a lazy tongs mechanism operated by the game body discharging means.

4. Game apparatus comprising a game body movable by gravity from an initial position to a lowermost position means for retaining a plurality of game bodies in the initial position, means for releasing the game bodies with short intermissions therefrom, means for conducting the game body from 80 such initial position to such lowermost position through any one of various paths, and common manually operable mechanism for returning the game body to its initial position and starting it from such initial position. 95

5. Game apparatus comprising movable game bodies, a game board having designated lodgment perforations, a spring-controlled false bottom for said game board having perforations corresponding to the perforations in the game board a magazine located at the upper portion of said game board, means within the magazine whereby only one game body is permitted to be released at a time, and commonly actuatable mechanism for operating the magazine to release a game body and for returning the game body to the magazine. 100 105

6. Game apparatus comprising movable game bodies, a magazine therefor, a game board having lodgment perforations, de-lodgment means, collecting means, a game body receiving part to receive the game body from the collecting means and a lazy tongs mechanism carrying such receiving part and operable by the downward, game body releasing movement of the magazine to return the game body to the magazine. 110 115

In testimony whereof I have affixed my 120 signature in presence of two witnesses.

JOHN W. WALLACE.
